UNITED STATES PATENT OFFICE.

IRVING T. EASTMAN, OF CODY, WYOMING, ASSIGNOR OF ONE-HALF TO ROY O. EASTMAN, OF MINNEAPOLIS, MINNESOTA.

DOUBLE-ACTING AIR PUMP.

Application filed January 5, 1922. Serial No. 527,120.

To all whom it may concern:

Be it known that I, IRVING T. EASTMAN, a citizen of the United States, residing at Cody, in the county of Park and State of Wyoming, have invented certain new and useful Improvements in Double-Acting Air Pumps; and I do hereby declare the following to be a full, clear, and exact description of the invention, such as will enable others skilled in the art to which it appertains to make and use the same.

This invention relates to an air pump and particularly to a small portable air pump adapted to be clamped to a board or other member and for use in pumping up automobile tires.

It is an object of this invention to provide such a pump having a large capacity and which is capable of producing a comparatively high pressure.

It is still a further object of this invention to provide a double-acting and double-cylinder pump, the cylinders being of different capacity and the air from the advancing side of the piston in the larger cylinder being delivered to the retreating side of the piston in the smaller cylinder.

It is still another object of the invention to utilize the pistons and piston rods as well as the common crosshead which actuates the rods, as the connecting means for delivering the air from one cylinder to another, thus doing away with the necessity of separate conduits or passages.

These and other objects of the invention will be fully set forth in the following description made in connection with the accompanying drawings in which like reference characters refer to the same parts throughout the different views, and in which,

Fig. 1 is a view in side elevation of the pump showing the same clamped in position;

Fig. 2 is a central vertical section of the cylinders and crosshead; and

Fig. 3 is a vertical section taken on the line 3—3 of Fig. 2.

Referring to the drawings, the device comprises a U-shaped clamp member 1, one leg of which is adapted to contact with one surface of a table or board and the other leg of which is equipped with a clamping screw 2 provided with a swivelly mounted head 3

and suitable handle 4. The upper arm of the member 1 has an upstanding lug thereon and to which a bifurcated arm 5^a is pivoted by a headed pivot pin 6 held in position by suitable means, such as a split key passing through the end thereof. The arm 5^a is integrally connected with and disposed under the cylinder head 5. This cylinder head 5 is in the shape of an oblong plate with circular ends, one end being of greater diameter than the other and is of substantially the same outline as the cylinder head 7 disposed at the other end of the pump and shown in Fig. 3. The cylinder heads 5 and 7 have shallow cylindrical recesses formed therein into which are fitted the cylinder barrels 8 and 9. The heads 5 and 7 are clamped together on the barrels 8 and 9 by spaced headed bolts 10 passing through lugs in the head 7 and threaded into corresponding lugs on the head 5. The head 5 is provided with raised bosses 5^b at the centers of its circular portions which form stuffing boxes and are threaded to receive the glands 11 threaded thereinto. The cylinder 8 is provided with a piston 12 and the cylinder 9 is provided with a piston 13, which pistons are provided with suitable packing or piston rings to form a tight fit with the cylinders. A piston rod 14 is secured to the piston 12 by being screwed therein and a piston rod 15 is similarly secured to the piston 13, these piston rods passing out at the front end of the cylinders through the stuffing glands 11, suitable packing material being compressed in the boxes 5^b about the rods by the said glands. The piston rods 14 and 15 are secured to a crosshead member 16 by being threaded thereinto and are locked in position in said head by suitable check nuts. The crosshead 16 is provided with spaced ears 16^a which embrace a lever 17 to which they are pivotally secured by a suitably held pivot pin. The lever will be, at its upper end, provided with a suitable handle, not shown, and is curved inwardly somewhat at its lower end and pivoted between spaced lugs 1^a projecting from the member 1. The piston 12 is provided with a passage or chamber 12^a and apertures opening on opposite faces of the piston communicate with this passage. The apertures also communicate with chambers equipped with check valves in the form of balls 18 pressed in

their seats by coiled springs 19, the springs abutting said balls at one end and at their other ends abutting screw plugs threaded into said valve chambers from the faces of 5 the piston opposite the apertures above noted. It will thus be seen that the apertures communicating with chamber 12^a are oppositely disposed and the valves controlling the same are, likewise, oppositely disposed. The piston rod 14 has a passage extending axially therethrough which is in communication with the passage 12^a. The crosshead 16 is also provided with a passage 16^b with which the passage in piston rod 14 10 communicates. A piston rod 15 is also formed with an axial passage therethrough communicating with the passage 16^b in the crosshead at one end and communicating at its other end with a chamber 13^a formed in 15 the piston 13. The piston 13 is also provided with oppositely disposed apertures in the face thereof communicating with the passage 13^a and these apertures are also controlled by spring pressed balls forming 20 check valves, the springs being held in place by threaded plugs 20 having central apertures therethrough. The crossheads 5 and 7 are provided with slightly upstanding bosses opposite the lower ends of the cylinder 8 forming check valve chambers, the 25 valves therein being also of the spring-pressed ball type, the springs of which are held in place by apertured and threaded plugs disposed on the inside of the chambers. These valves control apertures in the 30 top of said bosses communicating with the atmosphere. The cylinder heads 5 and 7 are also provided with chambers or passages 5^c and 7^c terminating at the inside of said 35 heads in threaded apertures and a suitably constructed conduit 21 is connected with these threaded apertures and is provided with a central discharge member 22 to which a flexible hose 23 may be connected. The 40 passages 5^c and 7^c communicate with valve chambers 5^a and 7^a having apertures communicating with the interior of the cylinder 9, these chambers being equipped with check 45 valves in the form of spring-pressed balls, the springs being held in place by a threaded plug screwed into the outside of the cylinder head.

The operation of the pump is as follows:

The pistons 12 and 13 will be reciprocated 55 by oscillating movement of the handle 17. Assuming the pistons to be in the position shown in Fig. 2, when the same move to the right, the air will be compressed between the right hand side of the piston 12 and the 60 right hand end of the cylinder 8. This compressed air will open the lower check valve shown in piston 12 and the air will pass therethrough and through the passage through piston rod 14 through the passage 65 16^b in the crosshead, through the passage

in the piston rod 15, will open the upper check valve shown in piston 13 and be delivered to the left hand or retreating side of the piston 13. This air being under pressure will assist in the movement of the piston 13. As the piston 13 moves to the right the air will be compressed between the same and the right hand end of the cylinder 9 and will open the check valve in chamber 5^a, pass through the passage 5^c into the discharge conduit 21 and will be discharged out through the tube or hose 23. The return of any of this air will, of course, be prevented by the check valve in chamber 5^a. As the piston moves to the left on the return stroke, the air under pressure delivered at the left hand side of the piston 13 will be prevented from again passing into the piston by the upper check valve of the piston and will open the valve in chamber 7^a passing 75 through the passage 7^c into the discharge conduit 21 to be discharged through the tube 23. This air will be prevented from passing back into the cylinder by the check valve in chamber 7^a. At the same time, the piston 12 will move to the left and the air compressed between this piston and the left hand end of the cylinder and will open the upper valve in the piston and pass through the piston rod 14 to crosshead 16 and piston rod 15, will be delivered through the lower valve in the piston 13 and to the right hand or retreating side of the piston. With each stroke of the pump, therefore, the air compressed in the larger cylinder will be delivered to the small cylinder and the air previously delivered to the smaller cylinder will be discharged at higher pressure. It will be noted that there is no inlet passage for air from the atmosphere to the high pressure cylinder 9. The air drawn into the pump will be taken at each stroke through the inlet valves in the ends of the cylinder 8.

From the above description it will be seen that applicant has provided an exceedingly simple and useful pump. By passing the air through the piston rods in the crosshead the structure is greatly simplified and many parts eliminated. The cylinders will oscillate about the piston 6 as the pump is oscillated and the tire or other member to which the air is to be delivered will soon be charged with air at a high pressure. The device is exceedingly compact, inexpensive to manufacture and can be quickly assembled. The parts can also be readily taken apart, if for any reason this becomes necessary. The pump can be quickly and easily clamped upon the running board of an automobile, 100 on a table, or other suitable support.

It will, of course, be understood that various changes may be made in the form, details and arrangement of the parts without departing from the scope of applicant's in- 105 110 115 120 125 130

vention, which, generally stated, consists in the matter shown and described and set forth in the appended claims.

What is claimed is:

5. 1. An air pump comprising high and low pressure cylinders, a piston in each cylinder, each piston having a chamber therein and passages communicating with opposite sides thereof controlled by oppositely acting 10 valves, piston rods for said pistons having longitudinal passages therethrough communicating with said chambers, respectively, the passage in the low pressure rod forming a discharge passage and the passage in the 15 high pressure rod forming an inlet passage, and means connecting the passages in said piston rods.

2. The structure set forth in claim 1, said low pressure cylinder having valve-equipped 20 inlet openings at each end and the high pressure cylinder having valve-equipped discharge openings on each end.

3. An air pump comprising two parallel cylinders of different diameters, a piston for 25 each cylinder and a piston rod connected with each piston, a crosshead connected to said rods for simultaneously moving the same, said pistons having oppositely facing valve-equipped openings in the faces thereof 30 communicating with chambers therein, and the chambers in said pistons in the respective pistons communicating with axial passages formed in the piston rods, said crosshead having a chamber therethrough communicating 35 with the passages in the piston rods whereby when the pistons are reciprocated, air will be delivered from the advancing side of the larger piston to the retreating side of the smaller piston.

40. 4. The structure set forth in claim 3, said larger cylinder being closed except for valve-equipped openings at each end communicating with the atmosphere and said smaller cylinder being closed except for 45 valve-equipped discharge passages at each end thereof, and a common discharge conduit communicating with said passages.

50. 5. A portable hand-operated double-acting compound pump comprising two parallel cylinders of different diameters, a piston in the larger cylinder having a chamber therein and inwardly opening valves in each face controlling communication with said chamber, a piston in the smaller cylinder 55 having a chamber therein, and outwardly opening valves controlling communication with the chamber therein, hollow piston rods connected, respectively, to said pistons and

communicating with the chambers therein, a crosshead connected to and adapted to operate said rods and pistons and having a passage therethrough communicating with the passages through said rods, air inlet means in the larger cylinder and discharge means in said smaller cylinder. 60 65

6. A compound double-acting pump having high and low pressure cylinders, pistons having chambers therein in said cylinders and hollow piston rods connected to said pistons and communicating with the chambers therein, means having a passage therein connecting said rods and the passages therethrough, one of said pistons having an inwardly opening valve in each face controlling communication with the chamber 70 75 therein and the other piston having an outwardly opening valve in each face, said valves controlling communication with the chambers in said piston.

7. A double-acting air pump having high and low pressure cylinders relatively rigidly mounted for oscillating movement, a piston for each cylinder, a rod connected to each piston having a longitudinal passage therethrough and projecting from said cylinders at one end, a cross head connecting said rods and having a passage connecting the passages therein, an oscillating lever pivoted to said crosshead, and means in said pistons whereby air is passed into and through said piston rods at each movement of said lever in either direction. 80 85 90

8. The structure set forth in claim 6, the high pressure cylinder having outwardly opening valves in the ends thereof and the low pressure cylinder having inwardly opening valves in the ends thereof. 95

9. A double-acting compound pump having high and low pressure cylinders, a piston in each cylinder having a chamber therein, each piston having check valves in both faces thereof controlling communication with the chamber therein, the valves in one piston working oppositely to the valves in the other, hollow piston rods connected to said pistons and communicating with the chambers therein and communicating with each other, inlet means in the high pressure cylinder and discharge means in the low pressure cylinder. 100 105 110

In testimony whereof I affix my signature.

IRVING T. EASTMAN.
